UNITED STATES PATENT OFFICE.

JOSIAH EMMETT, OF CHICAGO, ILLINOIS.

FIRE-EXTINGUISHER.

1,145,883.

Specification of Letters Patent. Patented July 13, 1915.

Application filed June 23, 1914. Serial No. 346,837.

To all whom it may concern:

Be it known that I, JOSIAH EMMETT, a citizen of the United States, and a resident of Chicago, in the county of Cook and 5 State of Illinois, have invented a certain new and useful Improvement in Fire-Extinguishers, of which the following is a specification.

This invention relates to fire extinguishers, and relates particularly to sprinklers for automatic sprinkler systems.

The primary object of the invention is to provide an improved fusible link or strut for such sprinkler which, in addition to the 15 requisites of strength and sensitiveness to heat, shall be safe and dependable in use, so that they will not break under the stresses to which they are subjected in use, until fused in the manner intended.

To this end, a fusible strut or link of my invention comprises the various features and details of construction herein-after described and claimed.

In the accompanying drawing, in which 25 my invention is fully illustrated, Figure 1 is a perspective view of a sprinkler head having a fusible link or strut of my invention. Fig. 2 is an enlarged front or face view of the side of the link or strut which is exposed in Fig. 1; and Fig. 3 is a sectional view of said link or strut on the lines 3—3 of Fig. 2.

Referring now to the drawing, A designates, as a whole, the frame of the sprinkler. 35 Said frame A may be of any desired or approved construction and will be readily understood by those familiar with the art without a detailed description thereof.

As shown, the sprinkler is of the type in 40 which the fusible link or strut is applied to secure the cap 1 in position to close the nozzle of said sprinkler, by means of what may appropriately and for purposes of convenient reference, be called toggle levers, respectively designated 2 and 3, the relation 45 being such that, in use, said link will be under tension. My improved link or strut may, however, be used in other usual and well known ways and I do not, therefore, 50 desire to limit myself to the manner of use shown.

My improved link or strut, designated as 55 a whole *a*, consists of only two members 4 and 5, which are made of suitable metal, being preferably stamped from sheet phos-

phor bronze and being of proper width and thickness to afford requisite strength, not only in the metal itself, but in the solder joint by which said strut members are connected. Operating in tension, relatively 60 thin metal may be used, a desirable thickness being about 17 gage sheet metal, while a solder joint of adequate strength will be provided by making said strut member five-eighths ($\frac{5}{8}$) of an inch wide. 65

The link or strut members 4 and 5 are of the same size and shape, thus requiring but a single pair of blanking dies for stamping the same, and are symmetrical on both sides of a longitudinal center line. To provide 70 for engaging the toggles 2 and 3 with the link or strut *a* and to permit said toggles to separate when said link fuses, each of the strut members 4 and 5 is provided with a hole 6 in one end thereof and a slot or 75 notch 7 in its opposite end, and said link or strut members are soldered together with the slot 7 in one end thereof in register with the hole 6 of the other, thus providing for pulling said link or strut members 80 apart endwise, as contemplated.

To increase the strength of the connection between the link or strut members 4 and 5, the links are provided, preferably at their centers, one with a projection 8 and the other 85 with a recess or socket 9 to receive said projection, the engaging sides of said projection and recess being inclined or tapered from the base to the tip or apex of said projection. As shown, the engaging sides of 90 said projection and recess are curved, being practically hemispherical. My invention, however, contemplates other forms of projection and recess and I do not, therefore, 95 desire to limit myself to the particular form shown. Also, to insure uniform and reliable operation of said link or strut and thus of the sprinkler, a hole or opening 10 is formed through the link or strut member in which the recess or socket 9 is formed, which will 100 permit any gases to escape which may be produced and which otherwise might accumulate at the bottom of said recess, by the soldering operation. Said hole or opening will also break the adhesion between 105 said link members due to the exclusion of the air. Also, to bring the line of the pull or tension of the toggles 2 and 3 in the plane of the contacting sides of said link or strut members, the extreme ends of said link or 110

strut members are off-set on opposite sides thereof a distance equal to one-half the thickness of said link or strut members.

The operation of my improved sprinkler 5 will be readily understood by persons familiar therewith, without a detailed description thereof.

I claim:—

1. A fusible link comprising overlapping 10 members soldered together, one of said members provided with a tapered socket and the other with a corresponding tapered projection which engages said socket, one thereof being provided with a vent hole 15 which communicates with said socket, substantially as described.

2. A fusible link comprising overlapping members soldered together, one of said members provided with a centrally located spherical socket and with a vent hole which 20 communicates with said socket, and the other with a corresponding centrally located spherical projection which engages said socket, substantially as described.

In testimony that I claim the foregoing 25 as my invention, I affix my signature in the presence of two subscribing witnesses this 20th day of June, 1914.

JOSIAH EMMETT.
